[57] CLAIM

The ornamental design for a compound bow stabilizer.

DESCRIPTION

FIG. 1 is a side elevational view of the compound bow stabilizer showing my new design;

FIG. 2 is a perspective view thereof;

FIG. 3 is a side elevation thereof, the article being symmetric about its axis;

FIG. 4 is an end view thereof; and,

FIG. 5 is an end view taken from the end opposite FIG. 4. The broken line showing of a bow in FIG. 1 is for illustrative purposes only and forms no part of the claimed design.
